UNITED STATES PATENT OFFICE.

FRANK A. TAGLIABUE, OF REVERE, MASSACHUSETTS.

STOVE SHIELD.

Application filed January 12, 1927. Serial No. 160,557.

My invention relates to stove shields.

The principal object of my invention is to devise a shield for use with cooking stove structures, and particularly with stoves of the so-called combination type, which is arranged to selectively isolate any desired portion of the cooking surface of a stove and accordingly prevent any spattering of grease, liquids, or other substances on to the remaining portion of said surface.

A further object is to devise a shield of the character described which may be utilized as a cover for the stove surface, or which may be entirely removed to permit of the use of the entire stove.

A further object is to devise a stove shield which shall be simple and durable in construction, cheap to manufacture, and which may be folded to serve as a simple cover for the cooking surface.

Articles of this character have heretofore comprehended either an arrangement which is an integral part of the stove and accordingly fixed in position, or they have been limited to serving as covers only for all or a portion of the cooking surface. The former is objectionable in that its use is limited to a particular area of the stove and also because it is not readily detachable as may be desirable under certain circumstances. The cover form of structure may be arranged to protect any desired area of the cooking surface, but it will not shield articles which may be placed on the cover for storage purposes.

As a solution of this problem, I have devised the shield which forms the subject matter of this application. Essentially, it comprises a pair of sheets of appropriate material which are hinged together, one of the sheets presenting a solid surface to serve as an upright shield, and the other which acts as a support therefor comprising an opening within the borders of which the cooking utensils are placed to have direct contact with the surface of the stove. The structure is free of any positive connection with the stove proper and hence may be moved to any indicated position, thus permitting one portion of the stove to be used for cooking and the remainder for storage or other purposes. In addition, when folded, the device may be used as a simple cover.

These and further objects of my invention will be set forth in the following specification, reference being had to the accompany-

ing drawing, and the novel means by which said objects are effectuated will be definitely pointed out in the claim.

In the drawing:

Fig. 1 is a plan view of the cooking surface of a combination stove showing my improved shield in position thereon.

Fig. 2 is a view looking in the direction of the arrow 2 in Fig. 1.

Fig. 3 is a perspective view of the stove shield as it appears normally.

In the drawing:

The numeral 10 represents a stove structure which, in the illustration shown, is of the combination type. The cooking surface thereof for the coal or wood end of the stove is denoted by the numeral 11 and in said surface, conventional plates 12 may be located.

In the gas burner end of the stove, burners 13 are located over which the usual grid 14 is placed. The parts heretofore described form no part of my invention, being the usual elements found in structures of this character.

My improved stove shield comprises a base 15 formed of any suitable sheet material and of any appropriate shape. An opening 16 is disposed within the borders of said base and a flange 17 along one side thereof, both flange and opening being provided for a purpose hereinafter explained. A shield 18, also formed of sheet material and of any appropriate shape, is pivotally secured to the base 15 in any approved manner, as by the hinges 19.

The use of the shield may be readily understood by referring to Figs. 1 and 2. Assuming that it is desired to use the gas burner end of the stove 10, the shield will be placed in position as indicated in said figures, i. e., the base 15 will be located so that the opening 16 registers with the burners 13, with the shield 18 standing in an upright position against the flange 17. By reason of the opening 16, it can be readily seen that pans and other cooking articles may be placed in direct contact with the gas flame, so that the cooking efficiency of the stove is not impaired by my device. The shield 18 serves to prevent soiling of the remaining surface of the stove, or of such articles as may be resting thereon. Accordingly, this portion of the stove may be utilized for storage purposes.

Moreover, since the shield is not an in-

tegral part of the stove, it can be moved to any desired location without disturbing its capacity to function properly, or it may be removed entirely. In addition, the shield is 5 adaptable for use as an ordinary cover merely by folding the elements thereof on each other.

While I have shown one set of elements and combinations thereof for effectuating 10 my improved shield, it is to be understood that the same is for the purpose of illustration only and in nowise to limit my device to the exact forms and structures shown, for many changes may be made therein without

departing from the spirit of my invention. 15
I claim:

A stove shield comprising a base having an opening for registering with a predetermined portion of a stove's cooking surface, a flange formed along one edge of said base, and a member pivotally secured to said base adjacent said flange, said member being arranged to be supported in an upright position by said flange for service as a shield. 20

In testimony whereof, I affix my signature. 25

FRANK A. TAGLIABUE.
